UNITED STATES PATENT OFFICE.

WILLIAM P. RANDALL, OF LE ROY, NEW YORK, ASSIGNOR TO JOSEPH S. L. PURDY, OF LE ROY, NEW YORK.

APPARATUS FOR FORCING FLUIDS FROM WELLS.

1,104,133.

Specification of Letters Patent. Patented July 21, 1914.

Application filed February 3, 1913. Serial No. 746,003.

To all whom it may concern:

Be it known that I, WILLIAM P. RANDALL, of Le Roy, in the county of Genesee and State of New York, have invented certain new and useful Improvements in Apparatus for Forcing Fluids from Wells; and I do hereby declare the following to be a full, clear, and exact description of the same, reference being had to the accompanying drawings, forming a part of this specification, and to the reference numerals marked thereon.

My present invention relates to apparatus employed for removing or expelling accumulations of oil and water in natural gas wells and it has for its object to provide an improved mechanism which may be inserted in the well, comprising a gas pressure chamber and an eduction pipe, together with a suitable arrangement of valve heads and seats located near the bottom of the well, whereby the fluid therein may be caused to rise into the eduction tube, above its normal level, and there entrapped and subsequently ejected by gas pressure introduced into the pressure chamber.

To these and other ends, my invention consists in certain improvements and combinations of parts all as will be more fully described hereinafter, the novel features being pointed out in the claims appended hereto.

In the drawings: Figure 1 is a vertical sectional view showing a mechanism constructed in accordance with my invention, and Fig. 2 is an enlarged view showing in detail, the lower end of the pressure chamber and the parts arranged therein.

Similar reference numerals in the several figures indicate the same parts.

An apparatus embodying my invention is adapted to be used in either shallow or deep drilled wells, which it will be understood, may be provided with one or more strings of casing, but in illustrating my invention, I have only shown a single casing A, extending from the surface of the ground to any desired depth. Within this casing is the gas tube B, its lower end extending to the bottom of the well, where it is provided with perforations b. The upper end of the gas tube projects from the mouth of the well and at a suitable intermediate point therein the space between it and the outer casing A is closed by the usual or any desired form

of packer a which prevents escape of the gas from the well requiring all of the gas issuing from the productive stratum of sand to pass upwardly within the tube B from which it may escape through the well line 60 pipe B', which is provided with the valve B'.

Connection is made between the pipes B, B' through the cross fitting C, which also receives the pipe c leading from the compression line D, the two latter pipes being 65 each provided with valves c' and d for controlling the flow of gas therethrough, since the compression line pipe D leads either from a larger distributing main, or well itself in which gas flows under high pressure, 70 or from a compression apparatus.

The gas compression chamber is in the form of a long tube E suspended within the gas tube with its lower end in proximity to the bottom of the well. The upper end of 75 this tube extends through the cross fitting C and is closed by a T fitting e, which is connected by the pipe e' with the compression line pipe D and is also provided with the shut-off valve e'. The gas tube B and 80 the compression chamber E are both secured in position at the mouth of the well by any suitable form of supports, and in the illustrations, I have shown the usual clamps comprising the plates 1, 2 and 3, the two latter 85 forming supports on which the fittings C and e rest.

The eduction pipe or siphon is a smaller pipe indicated by F, arranged within and movable longitudinally of the gas chamber 90 E and projecting from the upper end of the latter, where it is provided with any suitable device for raising and lowering it, as for instance, the lifting jack f, having the operating handle f', said jack resting against a 95 bearing or support f' carried on the uppermost clamping plate 3. At the upper extremity of the eduction tube is the discharge pipe controlled by the valve f'. The lower end of the pipe F is open and provided with laterally opening apertures f'', through which liquid may enter said pipe, as will be further described. This pipe is also provided at various points throughout its length, but preferably in its lower portion, 100 with a plurality of small perforations f'', which permit gas under pressure in the chamber E to enter the eduction tube for the purpose of raising and expelling the liquid entrapped therein.

It is desirable in apparatus of this nature, to prevent the entrance of liquid, to any appreciable extent, into the gas pressure chamber, principally because of the fact that the 5 fluid contains particles of sediment, which on account of the small areas of the perforations f^5 , will tend to clog these apertures, or some of them, and interfere with the successful gasifying, or aerating, of the 10 fluid column when this is being expelled. In order, therefore, to prevent the entrance of fluid into the pressure chamber, other than that which may leak through the fine perforations in the eduction tube, I arrange 15 between these two tubes at the lower end, a restriction G, which also serves as a guide for the lower end of the pipe F. In constructing these parts, I prefer to make the restriction G in the form of an inwardly extending ring on a sleeve or nipple, screwed in the coupling g attached to the lower end of the pipe E. I also provide this restriction 20 on its upper side with a valve seat g^2 , with which may coöperate the valve head f^6 , 25 formed on a tip piece or thimble secured to the lower end of the pipe F. On its lower side, the restriction G is provided with another valve seat g^2 with which engages the valve head H, which is normally held 30 against its seat, as shown in Fig. 2, by the gas pressure in the well, the head being guided in the spider h carried in the coupling h', on the lower end of the nipple g, said coupling also forming a connection for 35 the lower perforated foot or anchor E' on the extremity of the chamber E.

The operation of ejecting liquid from the bottom of the well, consists in first introducing fluid pressure into the well cavity to 40 expel the liquid into the eduction tube and thereafter directing the gas pressure into the chamber E and forcing the liquid upwardly out of the eduction tube. In carrying out these steps, the eduction pipe F is 45 lowered by the jack f and acting as a plunger engages the valve H and unseats it. The fluid in the well, acted upon by the gas pressure in the pipe B, passes upwardly through the spider h, and through the lateral openings f^4 into the pipe F until the 50 weight of the hydrostatic column thus created counterbalances the gas pressure in the well. The pipe F may then be retracted when the valve head H again seats itself. 55 At this time, the valve f^3 is open, and the valves c' , e^2 and B^2 are closed. After the valve H is closed, valves e^2 and d can be opened to connect the compression line D

to the chamber E. The pressure thus introduced into the chamber E will seek an outlet through the various perforations f^5 , 60 forcing the liquid in the eduction tube F upwardly, and as these perforations are located at various points in said pipe, the gas escaping through them serves to break up 65 and lighten the liquid column resulting in the discharge of a considerable volume of fluid, with only a small loss of gas.

I claim as my invention:

1. In an apparatus of the character described, the combination with a fluid pressure chamber and an ejection tube movable longitudinally therein, the lower portions of said chamber and tube being adapted to be submerged, of a valve normally closing the ejection tube against the entrance of fluid arranged to be opened by the movement of said tube and to admit fluid thereinto, said tube being provided with perforations for the inlet of gas from the surrounding chamber and means for introducing fluid under pressure into said chamber.

2. In a well cleaning apparatus, the combination with a fluid pressure chamber and an ejection tube movable longitudinally therein provided with a plurality of perforations located at different positions in its length, the lower ends of said chamber and tube being both adapted to be submerged, of a valve normally closing the tube and chamber against the entrance of liquid arranged to be operated upon the relative movement of the tube in opposite directions in the chamber to control the flow of liquid into the tube and means for controlling the flow of fluid pressure in the chamber to eject the liquid from the tube.

3. In a well cleaning apparatus, the combination with a well casing, an inclosed gas chamber therein extending approximately to the bottom of the well and provided with a valve seat, and a valve head normally held in engagement with its seat by the fluid pressure in the well, of a perforated siphon tube arranged in the chamber having an open lower end arranged to coöperate with the valve head and means for moving said tube longitudinally and a restriction located above said seat and between the chamber and tube and means for controlling the flow of fluid pressure into the chamber above the restriction.

WILLIAM P. RANDALL.
